J. F. MAYNE

WINDOW CLEANER

Filed Feb. 6, 1922

UNITED STATES PATENT OFFICE.

JAMES FRANK MAYNE, OF NORWALK, OHIO.

WINDOW CLEANER.

Application filed February 6, 1922. Serial No. 534,409.

To all whom it may concern:

Be it known that I, JAMES FRANK MAYNE, a citizen of the United States, and a resident of Norwalk, county of Huron, and State of Ohio, have invented a new and useful Improvement in Window Cleaners, of which the following is a specification.

My invention relates to window cleaners operated by power to reciprocate a wiper on the surface to be cleaned.

One of the objects of my invention is to eliminate the necessity of manual operation of the cleaner, another object is to clean the surface of both sides of the window at the same operation, another object is to provide adjustment for the wipers; another object is to automatically stop the wiper when encountering an obstruction, another object is to renew the wipers when worn; another object is an efficient means to stop and start the cleaner mechanism. Other objects will appear during the perusal of this specification.

I attain these objects by the mechanism illustrated in the accompanying drawing which show, by way of exemplification of the present invention, a windshield cleaner applied to an automobile, and in which Fig. 1 is a side view of an automobile windshield with a cleaner applied; Fig. 2 is an end view of Fig. 1; Fig. 3 is a section on line 3—3 of Fig. 6 (on larger scale); Fig. 4 is a section on line 4—4 of Fig. 6 (on larger scale); Fig. 5 is a section on line 5 of Fig. 3; Fig. 6 is a plan view of Fig. 1; and Fig. 7 is a section in line 7—7 of Fig. 3.

Similar reference characters refer to similar parts throughout the views.

During a storm, either rain or sand, the operator of a vehicle, such as an automobile, or street car, or locomotive, should direct his whole attention toward the road ahead and to the control of his vehicle and should not be required to divide his attention in order to clean windows so that he can see through them.

To avoid such division of attention of the operator and thereby avoid accidents, I have devised the present invention.

Referring now particularly to the drawing.

The windshield has the glass 10, and the frame 11 and is mounted in the housing 12 as will appear more in detail presently.

The shaft 13 is disposed on one side of the windshield and is journaled in the brackets

14 and 15 which are secured to the frame 11 and is also journaled in the brackets 16 and 17 which are secured to the housing 12. The shaft 13 has the gear 18 secured to one end and the body portion is reversely threaded, thus providing an endless thread like groove A which has leads in four different directions as follows: the portion 19 has a right hand lead, the portion 20 has a left hand lead and crosses the portion 19, the portion 21 leads from one end of the portion 19 to one end of the portion 20, and the portion 22 leads from the other end of the portion 20 to the other end of the portion 19. Thus providing an endless thread like groove having a right and left hand lead crossing each other.

In practice it may be convenient to first cut the right and then the left hand portions of the groove and then connect their ends by the portions 21 and 22.

The head B has a horizontal bore into which the outside of the shaft 13 fits rotatably, and also has a second horizontal bore, 80 at right angles to the other bore and opening thereinto.

The adjusting plug 23 is threaded into the outer end of this second bore, and the pawl block 24 is rotatably mounted in the inner 85 end of this second bore. The spring 25 is interposed between this plug and this block.

The head B further has an opening through which the endless cable 26 passes and also has the screw 27, threaded therein, 90 to firmly secure the head B to the cable 26.

The head B further has the projection 28 to which the wiper case 29 is secured by means of the screws 30.

The head B further has a third horizontal bore, parallel with the second horizontal bore. The adjusting plug 31 is threaded into the outer end of this third bore and bears against the roller block 32 which is slidably mounted in this third bore and is 100 prevented from rotation therein by the pin 33 mounted in the head B.

The roller 34 is journaled in the block 32 and bears against the frame 11.

The pawl block 24 is provided with the pawl 62 which fits into the groove A sideways at the top but is tapered downward and is comparatively wide to safely pass over the intersections of the groove A. The taper on the sides of the pawl 62 are provided to force the pawl block 24 back in the opening and disengage the pawl 62 from the

groove A when the cleaners encounter an obstruction.

The wiper case 29 is, preferably, formed of thin metal substantially in the form

5 shown sectionally in Fig. 7 and the wiper 35 is held therein by the screws 36 and bears against the glass 10.

10 The rod 37 is secured to the frame 11 by the screws 38 and has the flat surface 39 to prevent its rotation.

15 The head C fits slidably over the rod 37 and has a bore at right angles to the rod 37. The adjusting plug 40 is threaded into the outer end of this bore and bears against the roller block 41 which is slidably mounted in this bore and is prevented from rotation therein by the pin 42 mounted in the head C.

20 The head C also has an opening through which the cable 26 passes and also has the screw 43, threaded thereinto, to firmly secure the head C to the cable 26.

The roller 44 is journaled in the block 41 and bears against the frame 11.

25 The head C also has the projection 45 to which the wiper case 46 is secured by means of the screws 47.

30 The wiper case 46 is formed similar to the wiper case 29 and carries the wiper 48 which is held therein by the screws 49 and bears against the glass 10. The endless cable 26 passes over the four idlers 50 which are journaled in the brackets 51 secured to the frame 11.

35 The gear 52 meshes with the gear 18 and is supported by the bracket 53 which is secured to the housing 12.

40 The vertical shaft 54 is journaled in the brackets 55 secured to the housing 12 and has its upper end secured to the gear 52 while its lower end is connected to the flexible shaft 56.

45 The pinion 57 meshes with the usual speedometer gear 58 and is mounted on the shaft 59 journaled in the bracket 60 and adapted to slide endwise therein to engage or to disengage the gear 58.

50 The shaft 59 is moved lengthwise by means of the lever 61 conveniently located on the automobile, and is connected to the flexible shaft 56.

55 The wipers 35 and 48 are re-newable and may be made of any suitable material, preferably of felt, or rubber, or such other material which will readily remove water, snow, and dust without unduly scratching or abrasing the glass.

60 The wipers 35 and 48 can both be adjusted in relation to the glass by manipulating the adjusting plugs 23 and 40. In order to adjust the wiper 35, for instance, and bring it closer to the glass, as may become necessary due to wear, the adjusting plug 23 is screwed toward the glass, but since the head B is mounted on the shaft 13 and the roller 34 bears against the frame, the head B

swivels on the shaft and the upper portion of the head moves outward and the lower and wiper portion thereof moves inward toward the glass.

65 The wiper 48 is adjusted in a similar manner and swivels on the rod 37.

70 When either of the wipers encounters an obstruction sufficiently heavy to overcome the compression of the spring 25, the pawl 62 is forced out of the groove A due to its 75 taper sides and the pawl block 24 slides outward in its bore against the spring 25. As soon as the obstruction is overcome, the spring will force the pawl back into the groove again.

80 The operation of this apparatus generally is as follows: When the lever 61 is in the position shown in Fig. 1, the pinion 57 is in mesh with the gear 58 and rotates the shaft 59 and the flexible shaft 56 and the vertical shaft 54 and the gear 52. This gear 52 rotates the gear 18 and consequently the shaft 13.

85 When the shaft 13 rotates, the pawl 62, now supposed to be in the portion 19 of the groove A, follows the lead of this portion and moves the head B longitudinally on the shaft toward the portion 21 until the pawl arrives at the end of this portion 19. At this point, the pawl travels from the portion 19 into the portion 21 and from this portion 21 into the portion 20, whereupon the head B again travels longitudinally on the shaft 13 but in a direction opposite of the first travel until it arrives at the opposite end of the groove A. At this point, the pawl travels from the portion 20 into the portion 22 and then into the portion 19 whereupon the head B again travels longitudinally but opposite to the direction of this last travel. This back and forth travel of the head B continues as long as the gears 57 and 58 are in mesh or until one of the wipers encounters an obstruction and thereby forces the pawl out of the groove.

90 The head C is mounted on the rod 37 and can slide thereon longitudinally and the endless cable 26 is rigidly secured to the heads B and C. Consequently, when the head B travels in either direction, the cable 26 must follow and also cause the head C to travel but in a direction opposite to the head B.

95 This travel of the heads B and C and consequently the wipers 35 and 48 cleans both sides of the glass at the same time.

100 When it is desired to stop the travel of the wipers, the lever 61 is moved in the direction of the arrow until the pinion 57 abuts the bracket 60, at which point the pinion 57 and the gear 58 are out of mesh and the rotation of the shaft 59 and consequently the cleaner apparatus as a whole is arrested in its operation.

105 110 115 120 125 130 This cleaner mechanism does not interfere

with the opening of the windshield since it swivels on the shaft 13 which is journaled on the frame.

I am aware that modifications are possible to accomplish the aims of the present invention, within the scope of the appended claims. Therefore, without limiting myself to the precise construction shown and described,

10 I claim:—

1. The combination of a cleaner mounted for reciprocation on each side of a window, a reversely threaded shaft journaled on one side of said window, one of said cleaners 15 carried by said shaft and adapted to engage said threads thereon, the other of said cleaners carried by a rod secured to the other side of said window, and both of said cleaners connected by an endless cable.

20 2. The combination of a window frame, a shaft reversely threaded intermediate its ends and journaled on said frame, a window in said frame and hinged on said shaft, a cleaner carried by said shaft and provided 25 with means to engage said threads, and driving means for operating said shaft.

3. The combination of a window frame, a shaft reversely threaded intermediate its ends journaled on said frame, a window in said frame and hinged on said shaft which is disposed on one side of this window, a rod mounted on the other side of said window, a cleaner hingedly mounted on said shaft and provided with means to engage said threads for reciprocation on said shaft, a second cleaner hingedly mounted on said rod and adapted for reciprocation thereon, each of said cleaners provided with a yieldably mounted roller which bears on said window and tends to press the lower portion of said window against said window, idlers mounted on said window, an endless cable over said idlers, and both of said cleaners secured to said cable.

40 4. The combination of a window frame, a shaft reversely threaded intermediate its ends journaled on said frame, a window in said frame and hinged on said shaft which is disposed on one side of this window, a rod mounted on the other side of said window, a cleaner hingedly mounted on said shaft and provided with means to engage said threads for reciprocation on said shaft, a second cleaner hingedly mounted on said rod and adapted for reciprocation thereon, each of said cleaners provided with a yieldably mounted roller which bears on said window and tends to press the lower portion of said window against said window, idlers mounted on said window, an endless cable over said idlers, and both of said cleaners connected to each other for simultaneous reciprocation thereof.

45 5. The combination of a window frame, a shaft reversely threaded intermediate its ends journaled on said frame, a window in said frame and hinged on said shaft which is disposed on one side of this window, a rod mounted on the other side of said window, a cleaner hingedly mounted on said shaft and provided with means to engage said threads for reciprocation on said shaft, a second cleaner hingedly mounted on said rod and adapted for reciprocation thereon, each of said cleaners provided with a yieldably mounted roller which bears on said window and tends to press the lower portion of said window against said window, idlers mounted on said window, an endless cable over said idlers, and both of said cleaners secured to said cable.

55 6. In a window cleaner, the combination of, a window frame, a shaft journaled on said frame, a window hinged on said shaft and adapted to oscillate thereon, and a cleaner mounted for reciprocation and oscillation on said shaft.

65 7. In a window cleaner, the combination of, a window frame, a power shaft journaled on said frame and provided with a driving means, a window hinged on said shaft and disposed at one side thereof, a rod secured to the other side of said window, a cleaner mounted for reciprocation and oscillation on said shaft and reciprocated thereby, a second cleaner mounted for reciprocation and oscillation on said rod and connected with and operated by the first said cleaner.
